UNITED STATES PATENT OFFICE.

JOHN F. OSCARSON, OF BROCKTON, MASSACHUSETTS.

DOORCHECK.

Application filed November 8, 1924. Serial No. 748,624.

To all whom it may concern:

Be it known that I, JOHN FRITHIOF OSCARSON, a citizen of the United States, residing at Brockton, in the county of Plymouth and 5 State of Massachusetts, have invented certain new and useful Improvements in Doorchecks, of which the following is a specification, reference being had to the accompanying drawings.

10 This invention relates to door checks, and more particularly to that type of strap door check employed for limiting the opening of the door particularly with automobiles and the like.

15 An important object of the invention is to provide in a device of this character a construction such that sudden checking of the movement of the door, when the door reaches its limit of movement as defined by 20 the strap, is prevented, thus removing from the door and door post and the connections therebetween the strains to which they are ordinarily subjected.

25 A further object of the invention is to provide a device of this character which may be applied by anyone to the door without the use of any other tools than a screwdriver, and in which the application to the door may be made without marring the 30 surface of either the door or frame.

35 These and other objects I attain by the construction shown in the accompanying drawings, wherein for the purpose of illustration is shown a preferred embodiment of my invention and wherein:—

Figure 1 is a perspective view showing a door check constructed in accordance with my invention applied to a vehicle door;

40 Figure 2 is a sectional view through the yielding member of the check.

Referring now more particularly to the drawings, the numeral 10 indicates a strap of any suitable construction but preferably of some inextensible or substantially inex- 45 tensible material, such as heavy leather or rubberized canvas fabric such as is ordinarily employed in construction of drive belts. One end of this strap is provided with means, as at 11, whereby it may be secured to the vertical post 12 of a door frame, consisting in the present showing of a cleat, 50 about which one end of the strap 10 is secured, as at 13.

To the door proper is secured a metallic body 14 having openings 15 therethrough through which the securing elements may be

extended to attach the body to the door. The body extends horizontally of the door and is provided with a pair of spaced parallel longitudinally extending bores 16 opening 60 through one end of the cylinder. At the opposite end of the cylinder reduced bores 17 communicate with the inner ends of the bores 16. Through these reduced bores 17 are extended arms 18 of a U-shaped strap 65 clip, said arms having their extremities threaded and provided with nuts 19. Between these nuts 19 and the inner end walls of the bores 16, springs 20 surround the arms 18 and tend to urge the bight portion 70 21 of the U-shaped member toward the adjacent end of the metallic body 14. The opposite end of the strap 10 is passed about this bight portion and secured, as at 22.

The strap 10 in the construction thereof 75 is made of such length that it will of itself permit opening of the door only to a distance less than the normal amount of opening of the door. In other words, this strap of itself limits the movement of the door 80 prior to the complete opening thereof. When the door arrives at the limit of its movement as defined by the strap, tendency of the door to continue in its movement will place a strain against the U-shaped member 85 causing the arms of the same to shift longitudinally in the bores 16, so that the springs 20 are compressed between the nuts 19 and the inner end walls of the bores 16, thus applying a cushion to act as a final check of 90 movement of the door. Strain is thus removed both from the fastenings of the cleat 11 and the metallic member 14 as well as from the hinges of the door and the frame and post thereof. It will be obvious that a 95 strap of fixed length suddenly limiting movement of the door would tend to rack the frame of both the body to which one end of the strap was secured and the door to which the opposite end was secured.

100 Since certain changes and modifications may be resorted to in the construction of the strap without materially departing from the spirit of my invention, I do not limit myself to such specific structure as hereinbefore set forth except as hereinafter claimed.

I claim:—

1. Means for yieldably checking movement of a door with relation to the door post thereof including a strap secured at one end to one thereof, a metallic body 110

secured to the other thereof and having a pair of spaced parallel bores, a **U**-shaped member having its arms directed into said bores, springs engaging the arms of the **U**-shaped member and urging the arms in such direction as to urge the bight of the **U**-shaped member toward the metallic body, and a connection between the bight and the metallic body and the opposite end of the strap.

2. Means for yieldably checking movement of a door with relation to the door post thereof including a strap secured at one end to one thereof, a metallic body secured to the other thereof and having a pair of spaced parallel bores, a **U**-shaped member having its arms directed into said bores, springs engaging the arms of the **U**-shaped member and urging the arms in such direction as to urge the bight of the **U**-shaped member toward the metallic body, and a connection between the bight and the metallic body and the opposite end of the strap, said metallic body having a central portion located intermediate the portions of the body in which the bores are formed which is reduced and provided with open-

ings for the reception of securing elements.

3. Means for yieldably checking movement of a door with relation to the door post thereof including a strap secured at one end to one thereof, a metallic body secured to the other thereof and having a pair of spaced parallel bores, a **U**-shaped member having its arms directed into said bores, springs engaging the arms of the **U**-shaped member and urging the arms in such direction as to urge the bight of the **U**-shaped member toward the metallic body, a connection between the bight and the metallic body and the opposite end of the strap, the bores of said metallic body opening through one end of the body and at the opposite end of the body being reduced, the arms of the **U**-shaped member being introduced to the body through such reduced openings, the springs extending intermediate the shoulders formed at the last named ends of the bores, and nuts carried by and adjustable upon the extremities of said arms.

In testimony whereof I hereunto affix my signature.

JOHN F. OSCARSON.
